UNITED STATES PATENT OFFICE

2,669,488

GRANULAR MATERIAL HANDLING DEVICE

Barton S. Snow, Chicago, Ill., assignor to T. W. Snow Construction Company, Inc., a corporation of Illinois

Application August 17, 1951, Serial No. 242,225

8 Claims. (Cl. 302—11)

1

This invention relates to a device for transporting granular material and more particularly to a mobile unit for blowing such material from one place to another.

There are many industrial uses of granular material handling equipment such as the handling of dry sand in railroad yards for use in both steam and diesel locomotives. The sand is an especially dried sand which is generally stored in bins, buildings or tanks until it is to be used. This sand is transported to the railroad yard in boxcars and the use of this invention is particularly directed to the unloading of such boxcars.

The primary object of this invention is to provide an effective, inexpensive device for transporting granular material with a minimum of manual labor.

Another object of the invention is to provide a device for transporting granular material which is operated by compressed air.

A further object is the provision of a device of the character described which may be used to unload a storage bin, boxcar or the like, of practically all granular material contained therein.

One embodiment of the invention is illustrated in the accompanying drawings, in which:

Fig. 1 is a side elevational view of the device with certain parts cut away to show the interior thereof, and Fig. 2 is a top plan view of the device shown in Fig. 1 as viewed from a plane parallel to the screw conveyor.

Dry sand as used to fill the sand boxes of locomotives must be transported or carried in some manner from boxcars in which it is supplied to the railroads to a storage facility. Ordinarily a boxcar will contain about 40 tons of sand which will be used from time to time in the locomotives, with the storage facility being used to store the sand until it is actually used. Compressed air is usually available around railroad yards and provides an economical and readily available source of motive power for conveying the sand from one place to another through pipe lines. One system for conducting sand to a storage facility, and also from the facility to locomotive filling tanks is shown in my copending application Serial No. 125,908, filed November 7, 1949, now Patent No. 2,614,002. The system therein disclosed utilizes a sand pressure drum for blowing the sand from one place to another.

In the past a great amount of hand labor has been used for bringing the dry sand from a boxcar to the sand drum or other storage device. The sand was generally shoveled into a wheelbarrow and manually moved out of the boxcar to the drum. The present invention provides a de-

2

vice for automatically conveying the sand from the boxcar to the drum from which it may then be transported entirely by air pressure in pipe lines to other locations. The device picks up the sand by means of a screw conveyor which delivers it to a hopper, and an air jet is used to blow the sand through a discharge line to a point distant from the boxcar.

The device in its preferred form, as illustrated in Figs. 1 and 2, has a main frame utilizing a hopper 3 made of cylindrical pipe with wheels 4 secured to the lower portion thereof for moving the device from place to place. The hopper 3 is closed on its bottom end by a plate 5 and may be open upwardly or closed by a top plate 6 which extends rearwardly from the hopper 3 and joins rear framing plate 7 to which handle 8 is attached. The plate 7 is secured between the flanges 9 of a discharge nozzle 10. The nozzle 10 has an outer cylindrical casing 11 and an inner liner 12 telescoped therein to reduce abrasive wear of the granular material thereon. The structure thus far described comprises the base frame of the device.

25 Sand or other granular material is conveyed into the hopper 3 by means of a screw conveyor having a helical screw member 13 mounted loosely within a cylindrical housing 14 secured to the front of the hopper 3 and extending upwardly therefrom. The screw 13 has a shaft 15 which extends through the hopper and into a packing gland 16 mounted on the rear of the hopper and forming a bearing for the shaft 15. The forward end of the screw merely fits within the cylindrical housing 14 and rides therein as is normal procedure and structure in such conveyors.

30 The front or forward end of the conveyor housing supports a scoop 17 which has parallel sides 18 joined by a bottom 19 to form an upwardly open generally rectangular scoop. A screen 20 is positioned over the open end of the scoop to exclude material which will not pass the screen. This scoop is secured to the housing 14 by cooperating brackets 21 and 22 which are bolted or otherwise secured to the housing. The bottom 19 of the scoop is slightly curved so that the device may rest on the wheels 4 and the bottom of the scoop. In this manner the device may be pushed from place to place within a boxcar and 35 clean out substantially all of the sand therein.

35 The operating mechanism of the device secures its motive power from compressed air supplied through a small air supply line 25 which conducts air through an inlet line 26 to the inlet of 40 an air motor 27. Ordinarily air is available

around railroad yards at about 90 p. s. i. g. and such air may be used. The outlet 28 from the air motor exhausts air through a line 29 to the lower portion of the hopper 3 and through a jet nozzle 30 directed into the discharge port 10. A discharge line 31 is connected to the flange 9 on the discharge port 10 so that the nozzle 30 may blow sand from the hopper through the discharge line 31 to a point outside of the boxcar.

The inlet and outlet to the air motor are provided with suitable valves 32 and 33 and a by-pass line 34 extends between the inlet and outlet to the air motor to permit the operator of the device to direct air from the supply line 25 to the nozzle 30 without passing through the air motor. A valve 35 in the by-pass line has a simple push release control whereby the operator may quickly and easily permit air to take a direct path to the nozzle.

The air motor 27 is provided with a small sheave 36 and the shaft 15 of the screw is provided with a larger sheave 37 connected with the air motor by a V-belt 38 for driving the conveyor. When operating with air at 90 p. s. i. g., an air motor of about 900 R. P. M. capacity, arranged to drive the conveyor screw at about 250 R. P. M. will exhaust air at about 20 p. s. i. g. to the nozzle 30. Under such conditions about 4 to 5 tons of sand may be conveyed by the device in one hour's time. The conveyor should be driven at such a rate as to keep sand within the hopper at least to the conveyor level so that the jet will not blow back into the hopper rather than into the discharge port. If the device becomes clogged, the air motor will slow down and the operator may then permit some air to pass through the by-pass line 34 directly to the nozzle to clear out the clogging.

The device is rather light in weight and easily handled by a single man within a boxcar. Sufficient lengths of hose or pipes should be provided to permit the discharge line 31 to remain as nearly straight as possible since the sand may more easily be conveyed by the jet if the discharge line is straight. While the invention has been shown and described as embodied in a device particularly adapted to handle sand, it will be readily understood that the device is capable of handling other granular materials as well.

The foregoing detailed description is given for clearness of understanding only, and no unnecessary limitations should be understood therefrom, for some modifications will be obvious to those skilled in the art.

I claim:

1. A granular material handling device, for transporting material, comprising: a material receiving hopper having a material discharge port at its lower portion communicating with a discharge line; a material conveyor extending forwardly of and into the upper portion of the hopper for feeding material into the hopper; an air motor on the device driving said conveyor; a supply line of compressed air connected to said motor; an air jet at said discharge port directed into said discharge line; and an air line connecting said jet with the exhaust of said air motor.

2. A device as specified in claim 1, in which wheels are mounted on the hopper to facilitate movement of the device, and the front end of the conveyor is provided with a scoop to direct material into the conveyor.

3. A sand handling device, comprising: a sand receiving hopper having a discharge line con-

nected with its lower portion; a screw conveyor extending into the upper portion of the hopper and forwardly therefrom for feeding sand into the hopper; an air motor on the device driving the screw conveyor and having a supply line of compressed air connected to the motor; an air jet within the hopper directed into said discharge line; and an air line connecting the exhaust of the air motor with the air jet.

10 4. A device as specified in claim 3, wherein the screw conveyor has a housing opening into the hopper a distance above the discharge line not substantially less than the height of sand required to produce a head and provides a head of sand above the jet equal to the jet air pressure.

15 5. A device as specified in claim 3, wherein a by-pass line connects the air supply line with the air discharge line from the motor and a valve is positioned in said by-pass line whereby additional air may be directed to the jet.

20 6. A device as specified in claim 3, wherein wheels are provided on the device, and a scoop is provided on the forward end of the conveyor for directing sand into the screw, said device resting on the wheels and scoop whereby the device may be rolled from place to place and the scoop pushed into the sand to be moved.

25 7. A granular material handling device, comprising: an upwardly extending hopper having a laterally extending material discharge port in its bottom portion communicating with a discharge line; a screw conveyor extending forwardly out of the hopper above the outlet, said conveyor having a housing in which the screw is adapted to turn with the inner end of the screw being positioned within the hopper; a scoop on the forward end of the conveyor adapted to direct material to the screw; a compressed air line; an air motor connected to said air line and driving the screw at a rate to maintain material in the hopper; an air jet directed into the discharge port for blowing material from the hopper into said discharge line, said air jet being connected with the exhaust from said air motor.

30 8. A mobile granular material handling device, comprising: a closed receiving hopper having wheels mounted thereon; a screw conveyor mounted in a cylindrical housing secured to the upper part of the hopper and extending forwardly of the hopper; a scoop on the forward end of the conveyor housing for directing granular material to the conveyor; a source of compressed air; an air motor on the device coupled with the conveyor for driving the screw thereof, said air source being connected with the motor; a material discharge line near the bottom of the hopper; an air jet within the hopper directed into said discharge line, the exhaust from said air motor being connected with the air jet for blowing material from the hopper through the discharge line; and a by-pass air line from said air supply line to the air jet having a valve controlling admission of additional air to the jet.
